DESIGN FOR A COMBINED MIRROR AND ILLUMINATING STAND

Maurice Langbaum, New York, N. Y.

Application December 30, 1940, Serial No. 97,713

Term of patent 3½ years

To all whom it may concern:

Be it known that I, Maurice Langbaum, a citizen of the United States of America, residing in New York city, county of Kings and State of New York, have invented a new, original, and ornamental Design for a Combined Mirror and Illuminating Stand, of which the following is a specification, reference being had to the accompanying drawing, forming part thereof, wherein,

bined mirror and illuminating stand showing my new design.

I claim:

The ornamental design for a combined mirror and illuminating stand, substantially as shown.

MAURICE LANGBAUM,
